US00D663698S

(12) **United States Design Patent**
Allwood

(10) **Patent No.:** **US D663,698 S**
(45) **Date of Patent:** **** Jul. 17, 2012**

(54) **ASSEMBLY FOR DISPENSING CABLE**

(75) Inventor: **Brent David Allwood**, Buttaba (AU)

(73) Assignee: **ADC GmbH**, Berlin (DE)

(**) Term: **14 Years**

(21) Appl. No.: **29/393,774**

(22) Filed: **Jun. 9, 2011**

(30) **Foreign Application Priority Data**

Dec. 15, 2010 (AU) 15513/2010

(51) **LOC (9) Cl.** **13-03**

(52) **U.S. Cl.** **D13/155**

(57) **CLAIM**

The ornamental design for assembly for dispensing cable, as shown and described.

DESCRIPTION

FIG. 1 is a front perspective of an assembly for dispensing cable showing my new design;

FIG. 2 is a left side view;

FIG. 3 is a right side view;

FIG. 4 is a top view;

FIG. 5 is a bottom view;

FIG. 6 is a front view;

FIG. 7 is a rear view; and,

FIG. 8 is a front perspective view showing my design in a partially exploded view thereof.
